UNITED STATES PATENT OFFICE.

SIDNEY E. WILSON, OF LAUREL, MISSISSIPPI

REFRIGERATING SYSTEM.

Application filed July 15, 1928. Serial No. 122,632.

This invention relates to a refrigerating system, and its general object is to provide apparatus for this purpose, which is simple and inexpensive in construction, safe and reliable in its operation, and capable of developing the utmost efficiency for the amount of power consumed.

More specific objects of the invention include the provision of a special unloading device connected with the pump, which equalizes the pressure on opposite sides of the piston when starting; the provision of special intake ports in the pump cylinder, which increases the heat radiation to cool the pump; and the provision of a special expansion valve and parts associated therewith, which automatically act as an oil reservoir and a cooler of the liquid as it passes to the low pressure side of the system.

The above and other objects and advantages of the invention will be more particularly explained in the following detailed description, which is to be read in connection with the accompanying drawings illustrating one form in which the invention may be embodied.

In the drawings:

Figure 1 is a vertical sectional view of the complete system.

Figure 2 is an end elevation of the pump.

Figure 3 is an enlarged vertical section through the expansion valve and the parts associated therewith.

Figure 4 is a sectional view taken on the line 4—4 of Figure 3.

The present system has been devised with a view to using sulphur dioxide as the refrigerant, but it will be understood that the same principles may be used in connection with other refrigerating mediums.

The low pressure side of the system includes a brine tank 5, within the upper part of which is a flat chamber 6 for containing liquid refrigerant, and having numerous coils 7 extending downwardly from the bottom thereof into the lower part of the tank 5. Trays 8 are provided for containing whatever articles are to be chilled or frozen.

The upper side of the low pressure chamber 6 has a central upwardly extending neck 9, which has a threaded connection with a corresponding neck 10, extending downwardly from a casing 11, from which the refrigerant passes to the intake side of the

pump. In the normal operation of the system, the liquid refrigerant, in a state of ebullition, will fill the receptacle 6 and the coils 7, and will extend to the line indicated at 12 in the neck 10, and the casing 11 constitutes an oil reservoir which will normally be filled with liquid petrolatum, or whatever oil is used in the system.

An inner casing 13 is located within the outer casing 11, and carries at its lower end the expansion valve cage 14, which is formed with a nipple 15 extending downwardly into the chamber 6, and having a passageway 16 therethrough, which is controlled by the expansion valve 17. This valve has a conical lower end adapted to cooperate with a conical valve seat 18, and is provided with wings 19 which guide it vertically within the cage 14. The upper end of the cage 14 is formed with a yoke 20, and a lever 21 has one end fulcrumed at 22 to the yoke, and has an intermediate slotted connection 23 with the expansion valve, whereby to control the position of the latter. The free end of the lever 21 is connected by a link 24 to an intermediate portion of a lever 25, which has one end fulcrumed at 26 to the other side of the yoke 20. The free end of the lever 25 is pivotally connected to a stem 27, on which is secured a float 28, whereby the opening and closing of the expansion valve is controlled.

The inner casing 13 is extended upwardly, as at 29, and provided with a cap 30 to the center of which a nipple 31 is attached. A valve controlling stem 32 has a threaded connection inside the nipple 31, and is surrounded by a suitable packing gland 33. The lower end of the stem 32 is provided with a head 34 within a casing 35, secured to the upper side of the float 28 for controlling the float and needle valve. The casing 35 is provided with a drainage opening 35a.

The cap 30 is provided with an inlet port 36 through which the liquid refrigerant enters, and the outer casing 11 is provided with a port 37, through which the vaporized refrigerant is drawn back through the pump to the high pressure side. The high pressure side includes a tank 38 which is adapted to receive the liquefied refrigerant, which is forced upwardly through a pipe 39 to the port 36. This pipe 39 passes through a pipe 40 which leads from the outlet port 37, so that the liquid refrigerant, in passing into the low pressure side, is further cooled by the

cold rarified gas, which is passing back to the pump. The quantity of refrigerant contained in the tank 38 will vary due to the fact that it has in it only the liquid that is on the 5 way to the expansion valve. As soon as enough liquid accumulates in the expansion valve to raise the float, the discharge of liquid starts.

The pump for effecting the circulation of 10 the refrigerant comprises a crank case 41, which is suitably supported on legs 42, and which houses a crank shaft 43. One end of the crank shaft is provided with a wheel 44, which is driven by a belt 45 from a 15 wheel 46, secured to the shaft 47 of an electric motor 48, suitably mounted beneath the crank case. The crank case is provided with removable heads 49 and 50 in which the crank shaft is journaled, and the head 20 50 through which the crank shaft projects is provided with a suitable packing gland 51.

The pump cylinders 52 extend upwardly 25 from the crank case, and receive pistons 53 which are driven from the crank shaft 43. The heads of the cylinders 52 are provided 30 with removable plugs 54, in which check valves 55 are mounted. These check valves are normally held on their seats by coiled springs 56. As the pump is operated, the refrigerant, in a gaseous state, is compressed 35 and normally forced through a pipe 57 and condenser 58 where it is liquefied and passes into the liquid container 38. The pipe 57 is provided with a cut off valve 59, which must be closed when the system is being 40 pumped to a vacuum but open when charging the system with sulphur dioxide.

The intake end of the pump casing has 45 a removable cover 60, which is formed with an intake mouth 61, adapted to be connected by a suitable union 62 to the pipe 40 leading from the low pressure side of the system. The intake mouth 61 has a passageway 63 controlled by a valve 64, formed on the end 50 of a stem 65. A lever 66, fulcrumed at 67, on the cover 60, is intermediately connected to the stem 65, and its free end is received by a groove 68 formed on a collar 69, which is slidably mounted on the crank shaft 43 and controlled by a centrifugal governor 70. The cover 60 is also formed with a second 55 mouth 71, which is connected by a suitable union 72 to a bypass 73 leading from the head of the pump cylinders 52. The mouth 71 has a passageway 74 controlled by a valve 75 formed on the other end of the stem 65. The bypass 73 equalizes the pressure on opposite sides of the pump pistons when starting, to prevent overloading the 60 motor, but as soon as the pump gathers speed, the governor 70 closes the valve 75 and opens the valve 64. The gaseous refrigerant is then drawn from the low pressure side, and forced under pressure into the pipe 65 leading to the liquid receptacle 38.

In the operation of the pump, as each piston moves downwardly, the gas is admitted into the cylinder through grooves 76 in the wall of the cylinder, and as soon as the piston rises, this gas is compressed and forced past the valve 55. The grooves 76 extend spirally about the wall of the cylinder, and have their ends overlapping the opposite ends of the adjacent grooves. This construction not only enables the cold 75 gases in the grooves to come into contact with the entire circumference of the piston when it is in motion, thereby aiding materially in cooling the pump, but also equalizes the wear on the pistons and their rings. 80

The crank case 41 has an intermediate partition 77, which separates the cranks from the governor, and this partition also has a bearing for the crank shaft, which is provided with a packing gland 78. A conduit 79 leads from the lower part of the end of the crank case which houses the governor into the upper part of the crank housing, and provides a passageway for the gas and oil which pass over from the governor side 90 to the crank side of the casing. As it is desired to maintain a high oil level in the crank side of the case, the arrangement of the conduit permits practically all of the oil to be withdrawn from the governor side 95 of the case, where it enters through the passageway 63. The crank case 41 is provided with an intake valve 80, which is used in charging the system with the refrigerant. 100

In preparing the system for operation, the crank case is supplied with a suitable amount of lubricating oil, and a sufficient amount of lubricating oil is also introduced into the low pressure side to fill the outer casing 11. In order to introduce the sulphur dioxide into the system, the system must first be pumped to a vacuum. To do this connect a cylinder of sulphur dioxide to valve 80. Open valve 80. Open union between valve 59 and cylinder head of 105 pump. Close valve 59. Open expansion valve 17, by means of stem 32. Pump until a satisfactory vacuum has been created in the system. With motor running, close union between valve 59 and cylinder head of 110 motor. Open valve 59. Close expansion valve 17. Open valve on tank of sulphur dioxide. Pump until a given quantity of sulphur dioxide is stored in system. Valve 80 is then closed. The tank of sulphur dioxide is then disconnected. Before refrigeration can start, valve 17 must be adjusted by means of stem 32. 115

To start the refrigeration, the stem 32 is 120 adjusted until the head 34 is in neutral position. As the pump is now operated, the liquid refrigerant is forced upwardly through the pipe 39 and into the upper part of the chamber 13. It passes thence downwardly through the expansion valve 17, into 125

the receptacle 6 and the coils 7. The valve 17 is so controlled by the float 28 that the upper level of the liquid refrigerant will be established substantially on the line indicated at 12. The oil which was introduced into the low-pressure side and initially contained in the coils 7 has been forced upwardly by the heavier liquid refrigerant 5 gravitating into the coils 7, and floats on said refrigerant above the level 12. Thus, 10 the outer casing 11 becomes an oil reservoir from which the crank case is replenished. Some of the oil in the crank case works up 15 into the cylinder and eventually finds its way into the expansion valve, from which it is discharged along with the liquid refrigerant but, being lighter than the refrigerant, rises above the level of the same in the casing 11. As the liquid refriger- 20 ant within the receptacle 6 and coils 7 boils or bubbles, the gas formed thereby takes up latent heat which is abstracted from the brine, and chills the latter and the trays 8, which are surrounded thereby. The gas, 25 as fast as it is formed, is drawn through the pipe 40 to the pump, at the same time further cooling the liquid refrigerant in the pipe 39, which passes through the pipe 40.

No refrigerant except in the gaseous state 30 can pass from the low pressure side to the pump. This prevents any possibility of freezing the pump, or the pipes leading thereto. The vaporized refrigerant, and whatever oil circulates through the system, 35 passes through the pipe 40 to the governor chamber, and is drawn thence through the pipe 79 into the crank case. In the operation of the pistons the rarified gas passes through the spiral intake ports 72, thus exposing all 40 parts of the cylinder walls to the cooling action of the rarified gas. This increases the efficiency of the system.

The governor 70 and the valves 64 and 75 controlled thereby act automatically as a 45 special unloading device, equalizing the pressure at opposite ends of the pistons when the latter are moving slowly in starting. This makes it possible to operate the system with a small electric motor, which 50 is not equipped with a starter switch. As soon as the pump is stopped, the governor closes the valve 64, and opens the valve 75. This action of the governor also takes place if unfavorable condensing conditions should 55 arise to overload the motor and reduce its speed. This operation will be repeated until the gas on the high pressure side of the system has been sufficiently cooled to allow proper condensation.

60 The specially constructed expansion valve also acts as an oil reservoir. This valve controls the level of the liquid refrigerant, maintaining it substantially at the line indicated at 12, so that the oil floating on the 65 surface of the refrigerant, filling the space

within the casing 11, insures that any excess of oil in the low pressure side will be returned to the crank case along with the vaporized refrigerant.

The system can be used either with or 70 without a brine tank, and it can be used with either a pressurestat or thermostat, or without either.

While the invention has been designed with particular reference to sulphur dioxide 75 as a refrigerant, it is obvious that the same principles will apply to the use of other refrigerants. It is also apparent that many 80 modifications may be made in the details of the various parts of the system, as well as in the relative arrangement thereof without any material departure from the salient features of the invention as defined in the claims.

What is claimed is:—

1. In a refrigerating system, a condenser, a low pressure chamber having an upwardly projecting neck, a casing above said chamber and connected with said neck and having an outlet port in its top, an inner casing having walls spaced from the walls of the first-mentioned casing and having an inlet port in its top, a valve cage in the bottom of said inner casing and having a conduit leading therefrom through the neck into said chamber, a valve in said cage, and means controlling said valve to maintain the level of the liquid refrigerant normally within said neck. 95

2. In a refrigerating system, a condenser, a low pressure chamber having an upwardly 100 projecting neck, a casing above said chamber and connected with said neck and having an outlet port in its top, an inner casing having walls spaced from the walls of the first-mentioned casing and having an inlet port 105 in its top, a valve cage in the bottom of said inner casing and having a conduit leading therefrom through the neck into said chamber, a valve in said cage in cooperative relation to the mouth of said conduit, a system of levers within the inner casing for actuating the valve, and a float connected with said system of levers and controlling the valve so as to maintain the level of the liquid refrigerant normally within said 115 neck.

3. In a refrigerating system, a low pressure chamber, a condenser, a liquid receptacle, a passageway leading from said liquid receptacle to the low pressure chamber, a 120 casing interposed in said passageway, a valve in said casing, a float controlling said valve so as to maintain the liquid refrigerant in said low pressure chamber normally at a predetermined level, an outer casing surrounding said first-mentioned casing and forming an upward extension of the low pressure chamber and constituting an oil reservoir, a passageway leading from said casing, and a pump for drawing vaporized 125

refrigerant from said casing through said last-mentioned passageway and forcing it under pressure into the liquid receptacle.

4. In a refrigerant system, a low pressure chamber, a condenser, a liquid receptacle, a passageway leading from said liquid receptacle to the low pressure chamber, a casing interposed in said passageway, a valve in said casing, a float normally controlling said valve so as to maintain the liquid refrigerant in said low pressure chamber at a predetermined level, an outer casing forming an upward extension of said low pressure

chamber and surrounding the first-mentioned casing and constituting an oil reservoir, a passageway leading from said outer casing, a pump for drawing vaporized refrigerant from said outer casing through the last-mentioned passageway and forcing it under pressure into the liquid receptacle, and manually operable means connected with the float for positively closing said valve.

In testimony that I claim the foregoing as my own, I have hereto affixed my signature.

SIDNEY EUGENE WILSON.
